(57) **CLAIM**

The ornamental design for a portable outdoor air conditioner, as shown and described.

DESCRIPTION

FIG. 1 is a top, front and right side perspective view of a portable outdoor air conditioner showing my new design; FIG. 2 is a top, rear and left side perspective view thereof; FIG. 3 is a bottom, front and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a top, front and right side perspective view showing the portable outdoor air conditioner in a state of use;

FIG. 11 is a top, front and right side perspective view showing the portable outdoor air conditioner in another state of use;

FIG. 12 is an enlarged view of portion 12 in FIG. 1; and,

FIG. 13 is an enlarged view of portion 13 in FIG. 1.

The broken lines in the drawings illustrate portions of the portable outdoor air conditioner which form no part of the claimed design.
